UNITED STATES PATENT OFFICE

2,691,173

BATH APPARATUS

Alberta F. Smith, Marion, Ohio

Application July 21, 1952, Serial No. 299,994

2 Claims. (Cl. 4—1)

1

This invention relates to new and useful improvements and structural refinements in bath apparatus, and the principal object of the invention is to provide an apparatus which, in the nature of a garment, may be donned by a user for the purpose of taking a bath.

This object is achieved by the provision of a garment which is entirely waterproof in construction and completely incloses the user's body, the garment being provided with means for filling or flooding the same with water so that the body of the user is completely enveloped and bathed in the water without the necessity of utilizing a conventional bathtub or shower.

Apart from its primary purpose of furnishing bathing facilities, the invention may obviously be also employed for therapeutic purposes. Some of the other advantages reside in its simplicity of construction, in its efficient operation and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a perspective view of the invention.

Figure 2 is a fragmentary rear perspective view thereof.

Figure 3 is a fragmentary sectional view taken substantially in the plane of the line 3—3 of Figure 2 and

Figure 4 is a fragmentary cross sectional view, taken substantially in the plane of the line 4—4 in Figure 1.

Like characters of reference are employed to designate like parts in the specification and throughout the several views.

Referring now to the accompanying drawings in detail, the invention consists of a bath apparatus which is designated generally by the reference character 10 and embodies in its construction a watertight garment including a body portion 12, arm portions 14 and leg portions 16 which are connected to the body portion 12, the arm portions as well as the leg portions having closed extremities so that the garment is substantially watertight.

The body portion 12 is provided with a neck opening 18 and with an entrance slit at 20 which extends downwardly from the neck opening, this slit being disposed at the front of the body portion and being equipped with a watertight closure in the nature of a slide fastener 22.

2

The chest region of the body portion 12 consists of an outer wall 12' and a foraminous inner wall 24, these two walls defining therebetween a water jacket 26 having a filler opening 28 adjacent to the neck opening 18. The filler opening is equipped with a suitable filler plug 30.

The leg portions 16 are provided adjacent the lower extremities thereof with a pair of drain plugs 32, and if desired, the "soles" or undersides 10 of the foot regions of the leg portions 16 may be formed with traction increasing treads 34 to prevent any possibility of slippage.

The body portion 12 of the garment is provided at the back of the neck opening 18 with an apertured lug 36 whereby the entire garment may be conveniently suspended from a hook or hanger when it is not in use.

When the invention is placed in operation, the filler plug 30 is removed and warm or hot water is poured into the chamber 26 through the opening 28, which water, in turn, gravitates through the foraminous inner wall 24 and completely fills the entire garment including the arm and leg portions thereof, so that the bather's body is completely enveloped by the liquid. Subsequently, the liquid may be drained from the garment by simply removing the drain plugs 32 as will be clearly apparent.

If desired, drain plugs 38 may also be provided adjacent the closed extremities of the arm portions 14, so that the user need not raise his arms in order to drain liquid from the arm portions.

It is believed that the advantages and use of the invention will be readily understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. A bath apparatus of the character described, comprising a watertight garment including a body portion and arm and leg portions connected thereto, said body portion being provided with a neck opening and with an entrance forming slit extending from said opening, a watertight closure for said slit, said arm and leg portions having closed extremities, a water filler plug provided on said body portion adjacent said neck opening, drain plugs provided on said leg portions

adjacent the closed extremities thereof, drain plugs provided on said arm portions adjacent the closed extremities thereof, and foraminous water jacket provided in said body portion, said filler plug communicating with said jacket, said jacket permitting water to contact the body of the wearer.

2. A bath apparatus of the character described, comprising a watertight garment including a body portion and arm and leg portions connected thereto, said body portion being provided with a neck opening and with an entrance forming slit extending from said opening, a watertight closure for said slit, said arm and leg portions having closed extremities, a water filler plug provided on said body portion adjacent said neck opening, drain plugs provided on said leg portions adjacent the closed extremities thereof,

drain plugs provided on said arm portions adjacent the closed extremities thereof, said body portion including a chest region having an outer wall and a foraminous inner wall defining a water jacket therebetween, said outer wall having a filler opening adjacent the top thereof, and said filler plug being disposed in said filler opening.
